UNITED STATES PATENT OFFICE.

WALTER C. WESTAWAY, OF ROCKFORD, ILLINOIS, ASSIGNOR, BY DIRECT AND MESNE ASSIGNMENTS, TO J. W. DUNTLEY, OF CHICAGO, ILLINOIS.

CARBURETER.

968,215.

Specification of Letters Patent. Patented Aug. 23, 1910.

Application filed November 24, 1906. Serial No. 344,831

To all whom it may concern:

Be it known that I, WALTER C. WESTAWAY, a citizen of the United States, residing at Rockford, in the county of Winnebago and State of Illinois, have invented certain new and useful Improvements in Carbureters, of which the following is a description.

My invention belongs to that general class 10 of devices designed to thoroughly commingle air and a suitable liquid, as for example a hydro-carbon, and has for its object the production of a similar, cheaper and more efficient device for the purpose.

15 To this end my invention consists in the novel construction, arrangement, and combination of parts herein shown and described, and more particularly pointed out in the claims.

20 In the drawings wherein like reference characters indicate like or corresponding parts: Figure 1 is a partial vertical sectional view of one form of my device. Fig. 2 is a cross-sectional view of the same taken on line 25 2—2 of Fig. 1. Fig. 3 is a view of one side in elevation. Fig. 4 is a view of the opposite side in elevation. Fig. 5 shows my preferred form of liquid valve, the ports shown in dotted lines. Fig. 6 is a sectional view 30 of the same taken on line 6—6 of Fig. 5. Fig. 7 shows my preferred form of valve, in a slightly different position relative to the port openings. Fig. 8 shows the same, the valve shifted until the port openings are 35 wide open. Fig. 9 is a partial vertical sectional view of a modified form of device, and Fig. 10 is a top view of the device shown in the several figures.

40 Referring to the drawings, 1 is a base and 2 a top for a shell or casing forming a mixing chamber. The base and top may be secured together in any suitable or preferred way. As is shown in the drawings (see Figs. 2, 3 and 4) lugs 3, 3 suitably 45 formed on the two parts 1 and 2 serve as seats for the clamping bolts 4 or their equivalents, which securely hold the parts together.

Within the mixing chamber is a suitable 50 spreader or baffle 9 (Figs. 1 and 2), preferably integrally connected to the part 2 as at 10, but arranged so as to leave an open space 11 between it and the part 2. It is obvious that if desired the spreader may be 55 made separate from the part 2, and secured

in the preferred position by any suitable means. The top 2 is preferably extended as at 2', and a valve seat 13 arranged thereon as shown. Means for conducting a liquid from the valve seat to substantially the center of the under part of the spreader is provided, the preferred construction being to have the duct 12 for that purpose arranged within the spreader as shown. Any suitable means may be employed for conducting 60 the liquid from the supply pipe to the valve seat, a second duct 15 extending from the supply pipe opening at 15' to the valve seat is shown for the purpose. A valve 14 for controlling the passage of liquid through the 65 ducts 15 and 12 to the spreader is provided, the construction and operation of which will be more fully explained hereafter.

In the preferred construction, suitable means are provided for admitting air to the 70 mixing chamber, as shown an opening 8 is arranged for that purpose. The base 1 preferably extends up into the mixing chamber forming a nozzle as at 7, and is provided with a chamber 6 formed by the walls 5. It 75 is obvious that the extension 7, or the walls 5 forming the chamber 6, may be made separate from the base 1, and secured thereto in any suitable or preferred manner, if the same is so desired, instead of integral as 80 shown. A suitable valve 16 for regulating the amount of air admitted to the chamber 6 is shown, the construction and operation being more fully explained hereinafter.

In the upper part of the top 2, is provided 90 an outlet opening 17. As shown the top is extended as at 18, and suitable means provided for attaching the same to a pipe, engine or the like, lugs 44 being found satisfactory.

95 My preferred form of valve for controlling the liquid admitted to the duct 12 consists of the member 14 pivotally secured to the top 2 as at 19 (see Fig. 3). The valve is securely held on its seat 13 by the member 21 secured to the top 2 as at 22, the member 20 and the resilient means 23. The part 20 preferably extends out as at 20' to loosely engage 21, in order that the part 20 may be retained in a suitable position to 100 perform its functions in holding the valve on its seat. The construction of the valve is clearly shown in detail in Figs. 5, 6, 7 and 8. A depression 14' is formed in the valve on the side that seats on the valve seat 110

13. When the valve is substantially in the position shown in Fig. 3, the ports (as shown in dotted lines) are closed and liquid prevented from passing from the supply pipe, through duct or port 15 to the port or duct 12. As the valve is operated the ports are gradually opened to each other as indicated in Figs. 5, 7 and 8, as shown being wide open in the position in Fig. 8.

The preferred form of valve for regulating the amount of air to the chamber 6 and opening 8 is most clearly shown in Fig. 4. The part 34 is pivotally secured to the base 1 as at 36, and carries one or more adjustable members 16, which are adapted to cover or partially cover the opening to the chamber 6. It is obvious that instead of using the adjustable members 16, held by the screws 35 or other suitable means, a flat not adjustable member might be used, that is the member 34 might be of a shape adapted to cover the opening to the chamber 6. The top 2 is also preferably provided with extensions 24, or their equivalent, adapted to hold the member 25, to which is secured the lever or arm 40. (See Fig. 10.) Any suitable means may be employed to operate the inlet valves, and the same may be operated separately or synchronously as is desired or preferred. My preferred way and means are substantially as follows. Arms or levers 26 and 30, or their equivalent are secured to the member 25. The liquid valve and air valve are connected to the arms 26 and 30, by means of the connecting members 27 and 31 pivotally secured at the points 29 and 28, and 33 and 32, to the valves and arms respectively. It is obvious that the extent to which either of the valves is opened depends upon the rotation or movement of the lever or arm 40, and that the two inlets are opened synchronously and to a predetermined extent relatively to one another.

In my preferred form of construction as indicated in Fig. 9, the spreader 9 is extended downward as at 37 or substantially dome shape, it being obvious that the extension may be separate from 9, as shown, or integral. In this form the member 38, substantially as shown, may be provided.

The mode of operation of my improved device is substantially as follows. Normally the solid portion of the valve 14 covers the port 12 and prevents the passage of liquid into the port or duct 12, and into the mixer. Upon rotating the lever 40 the valve moves and gradually uncovers the port 12 and the liquid passes from the supply pipe through the duct 15, through the recess 14' and into the duct 12, thence into the mixing chamber. By the same movement of the arm 40, the air valve 16 is opened and air is admitted to the mixing chamber through the chamber 6 and opening 8. The incoming air strikes the spreader and the incoming

liquid. The liquid and air commingle and (in the simple form of device shown in Figs. 1 and 2) pass up through the opening 11 and thence up and out through the outlet or opening 17 to the engine or other desired place. In the preferred form shown in Fig. 9, the mixture passes down and under the edge of the extension 37, and then upward through the openings 11, and out of the outlet 17. As is shown a small opening 75 or duct 39 is preferably provided opening down into the chamber 6. Any water that may form or be in the mixture chamber owing to moisture in the air or other causes, or any excess of liquid from the liquid inlet duct, will run off through this opening to the chamber 6 and out, or else be drawn back into the mixing chamber in the form of vapor or gas. In this manner the flooding of an engine or the like, with the liquid 80 is practically done away with. The lever or arm 40 is preferably provided with an extension 43, and also an extension 41 and an adjustable member 42. These extensions and the adjustable member serve to regulate 85 the travel of the arm 40. An adjustable member may be put on the extension 43 if desired, or any other suitable means may be employed instead of these extensions, to regulate the movement of the lever 40. 95

It is thus seen that I have an efficient and very simple device for accomplishing the purpose set forth, and as it is obvious that the arrangement of the various parts as shown may be altered and other various immaterial modifications made without departing from the spirit of my invention, I do not therefore wish to be understood as limiting myself to the exact construction and arrangement shown. 100

What I claim as new and desire to obtain by Letters Patent is:—

1. A carbureter comprising a shell or casing inclosing a mixing chamber, a baffle plate positioned transversely of said chamber, and a liquid inlet formed in said baffle plate and having an outlet in one face of the plate, in combination with an air inlet positioned directly opposite said liquid outlet, an outlet upon the opposite side of said baffle plate, and means for controlling the said air and liquid inlets. 115

2. A carbureter comprising a shell or casing inclosing a mixing chamber, a baffle plate positioned transversely of said chamber, and separating said chamber into an upper and lower section having a communicating passageway, a liquid inlet in said baffle plate, substantially at its center, in combination with an air inlet in one section 120 directly opposite said liquid inlet and an outlet in the other section, and means for controlling said air and liquid inlets. 125

3. A carbureter comprising a shell or casing inclosing a mixing chamber, a baffle 130

plate positioned transversely of said chamber, and separating the same into opposite sections, said baffle plate being separated at its side from the casing to form a passage 5 and having a liquid inlet formed therein, in combination with an air inlet, said air inlet being arranged to direct the entering air against said baffle plate at the inlet therein, an outlet to the opposite side of the baffle 10 plate, and means for controlling said air and liquid inlets.

4. A carbureter comprising a shell or casing having intermediate its ends a transversely extending spreader plate, separated 15 at its side from the interior wall of the casing to constitute a communicating passage way, said spreader plate having a longitudinally extending liquid inlet therein opening outwardly through one face thereof, an air 20 inlet directed against said face, and an outlet in the casing to the opposite side of said spreader.

5. A carbureter comprising a shell or casing inclosing a mixing chamber, an outlet, a 25 dome shaped baffle plate positioned transversely of said chamber, and a liquid inlet in said baffle plate to the opposite side of said outlet, in combination with an air inlet positioned directly opposite said liquid inlet 30 and within the dome and said baffle plate being separated from the side of the casing whereby the mixture will be directed downwardly along the surface of the dome and through the passage way therebetween 35 and the casing.

6. A carbureter comprising a shell or casing having intermediate its ends a transversely extending spreader plate separated 40 at its side from the interior wall of the casing to constitute a communicating passage way, said spreader having a longitudinally extending liquid inlet therein opening outwardly through one face thereof, an air inlet nozzle projecting through the bottom of 45 the casing and having its outlet end adjacent to the face of the spreader so as to direct the air directly thereagainst, and an outlet in the casing to the opposite side of the spreader.

50 7. A carbureter comprising a shell or casing inclosing a mixing chamber, a baffle plate positioned transversely of said chamber, and a liquid inlet extending longitudinally through said baffle plate and opening 55 outwardly through one face thereof substantially at its center, in combination with an air inlet positioned directly opposite said liquid inlet arranged to direct the entering air against said baffle plate, an outlet positioned at the opposite side of said baffle plate, and means for controlling said air and liquid inlets.

8. A carbureter comprising a shell or casing inclosing a mixing chamber, a dome-shaped baffle plate positioned transversely 60

of said chamber, and a liquid inlet extending longitudinally through said baffle plate and terminating in a transverse outlet substantially at its center, in combination with an air outlet positioned directly opposite said liquid inlet arranged to direct the entering air against said baffle plate, said baffle plate being separated from the casing so as to form a passage way therearound, an outlet positioned at the opposite side of said baffle plate, and means for controlling said air and liquid inlets.

9. A carbureter comprising a shell or casing inclosing a mixing chamber, a dome shaped baffle plate, positioned transversely 70 of said chamber, and a liquid inlet in said baffle plate, substantially at its center, in combination with an air inlet and an outlet positioned at opposite sides of said baffle plate, said air inlet being arranged to direct the entering air against the dome shaped interior of said baffle plate at said liquid inlet whereby, said liquid and air will be directed downwardly and outwardly toward the edge of said plate, which latter is separated from the wall of the casing.

10. A carbureter comprising a shell or casing inclosing a mixing chamber, a dome shaped baffle plate positioned transversely 75 of said chamber, and a liquid inlet in said baffle plate substantially at its center, in combination with an air inlet and an outlet positioned at opposite sides of said baffle plate, said air inlet comprising a nozzle arranged to direct the entering air against 80 said plate at said liquid inlet, and valve mechanism for synchronously adjusting said air and liquid inlets.

11. A carbureter comprising a shell or casing inclosing a mixing chamber, a baffle 85 plate positioned transversely of said chamber, and a liquid inlet in said baffle plate substantially at its center, in combination with an air inlet and an outlet positioned at opposite sides of said baffle plate, said air inlet comprising a nozzle arranged to direct 90 the entering air against said plate at said liquid inlet, and means for controlling said air and liquid inlets.

12. A carbureter comprising a shell or casing inclosing a mixing chamber, a dome-shaped baffle plate positioned transversely 95 of said chamber, and separated from the side of said chamber to form a passage way, said plate being arranged to direct the liquid and air downwardly and outwardly to said passageway and a liquid inlet in said baffle plate substantially at its center, in combination with an air inlet positioned directly opposite said liquid inlet, an outlet, 100 and means for synchronously adjusting said air and liquid inlets.

13. A carbureter comprising a shell or casing inclosing a mixing chamber, a dome shaped baffle plate positioned transversely 105

- of said chamber, and a liquid inlet in said baffle plate substantially at its center, in combination with an air inlet and an outlet positioned at opposite sides of said baffle plate, said air inlet comprising a nozzle arranged to direct the entering air against said plate at said liquid inlet, and means for synchronously adjusting said air and liquid inlets.
- 10 14. In a device of the kind described, a casing comprising a base and a top, said top provided with a liquid inlet and an outlet, said base provided with an air inlet, in combination with a baffle plate arranged in said
- 15 top, a nozzle for directing air from the air inlet against said baffle plate, a duct for conducting liquid from the liquid inlet to said baffle plate, a valve for gradually controlling said liquid inlet to the baffle plate, and
- 20 means for controlling said air inlet, and mechanism for synchronously operating said controlling means.
15. In a device of the kind described, a casing adapted to form a chamber, and provided with a liquid inlet, an air inlet and an outlet, in combination with a baffle plate arranged within said chamber forming substantially a mixing chamber and a receiving chamber, a nozzle for directing air from the air inlet against said baffle plate, a duct for conveying liquid to the receiving chamber, a valve for gradually controlling the amount of liquid admitted to the receiving chamber, and an adjustable valve for controlling the amount of air admitted to the receiving chamber. 25 30 35

In testimony whereof, I have hereunto signed my name in the presence of two subscribing witnesses.

WALTER C. WESTAWAY.
